(57) **CLAIM**

The ornamental design for a packaging for lipped containers, as shown and described.

DESCRIPTION

FIG. 1 is a perspective view of a packaging for lipped containers in an unfolded state, according to the invention, where the evenly spaced broken lines represent claimed fold lines; FIG. 2 is a top view of the packaging for lipped containers of FIG. 1 in an unfolded state, where the evenly spaced broken lines represent claimed fold lines; FIG. 3 is a bottom view of the packaging for lipped containers of FIG. 1 in an unfolded state, where the evenly spaced broken lines represent claimed fold lines;

FIG. 4 is a front view of the packaging for lipped containers of FIG. 1 in an unfolded state; FIG. 5 is a rear view of the packaging for lipped containers of FIG. 1 in an unfolded state;

FIG. 6 is a left side view of the packaging for lipped containers of FIG. 1 in an unfolded state; FIG. 7 is a right side view of the packaging for lipped containers of FIG. 1 in an unfolded state;

FIG. 8 is a top view of the packaging for lipped containers of FIG. 1 in a folded state; FIG. 9 is a bottom view of the packaging for lipped containers of FIG. 1 in a folded state;

FIG. 10 is a perspective view of two of the packaging for lipped containers of FIG. 1, each in a folded state, with the lipped container, which is shown in phantom and forms no part of the claimed design; and, FIG. 11 is a perspective view of a packaging for lipped containers of FIG. 1 in a folded state, with the lipped container, which is shown in phantom and forms no part of the claimed design.

The evenly spaced broken lines in the drawings represent claimed fold lines. The phantom lines showing the lipped container(s) are for illustrative purposes only and form no part of the claimed design.
